CLAIM

The ornamental design for a videotape splicing and repair kit, substantially as shown.

DESCRIPTION

FIG. 1 is a top plan view of a videotape splicing and repair kit showing my new design;

FIG. 2 is a front elevational view thereof;

FIG. 3 is a perspective view thereof with the cover and tools removed;

FIG. 4 is a sectional view taken on line 4—4 of FIG. 1;

FIG. 5 is an underside view thereof;

FIG. 6 is a side elevational view as taken from the right hand side of FIG. 3; and

FIG. 7 is a rear elevational view thereof.
